UNITED STATES PATENT OFFICE.

ALMYR L. NEWMAN, OF WARWICK, RHODE ISLAND, ASSIGNOR TO A. L. NEWMAN COMPANY, OF CRANSTON, RHODE ISLAND, A CORPORATION OF RHODE ISLAND.

CLASP FOR BRACELETS AND LIKE ARTICLES OF JEWELRY.

Application filed May 2, 1925. Serial No. 27,477.

This invention relates to clasps for watch-bracelets or other articles of jewelry and consists of improvements in the construction of the same.

5 One object of the invention is to provide an article of the type specified for clasping the bracelet to the watch, and for other like purposes, which is simple in construction, economical to manufacture, and efficient in 10 use for the purpose described.

Other objects of the invention are to provide a clasp which may be easily attached to the loop of the watch or other article and which will be securely held from accidental unfastening, while being durable in 15 use and proof against derangement or getting out of order.

Further objects of the improvement are set forth in the following specification which 20 describes a preferred embodiment of the invention as illustrated by the accompanying drawings, in which:

Fig. 1 shows the improved clasp as applied to the ends of a bracelet or strap to 25 fasten the same to a wrist watch;

Fig. 2 is an enlarged side elevation of the clasp;

Fig. 3 is an enlarged bottom plan view 30 of the same, showing the latch or keeper of the clasp in both closed and open position;

Fig. 4 is a perspective view of the main hook-portion of the clasp;

Fig. 5 is a perspective view of the latch-holding part of the clasp; and

Fig. 6 is a perspective view of the latch or keeper.

Referring to the drawings, my improved clasp is preferably constructed from sheet-metal punched or stamped out in suitable 40 dies. As shown in Fig. 4, the main portion

2 of the clasp comprises a substantially rectangular strip of sheet-metal having side wings or ears 3 bent downwardly at right-angles to adapt them to enclose the edges of

45 the strap, band, or bracelet 4 which has its end attached to the clasp in any suitable manner. The flat length of the strip is ex- 50 tended in a widened portion 5 which is bent around to form a hooked beak 6 adapted to

55 engage the loop 7 on the side of the watch 8, as shown in Fig. 1.

To the box-like portion 9 of the main member 2 of the clasp is attached a latch-carrying member 10 which extends across

the bent-down wings or side-ears 3 to close 55 the box in the form of a tube. The member 10 is constructed from a rectangular blank of sheet-metal which is folded along a medial line to provide an envelope-shaped structure as illustrated in Fig. 5. Bent upwardly at an angle to the folded strip 10 is a tab 11 adapted to bridge the space between the ends of the bent-over ears 3 on the main member 2, and to be soldered or otherwise secured thereto to close the forward side of 60 the box or tube, while providing a beveled or inclined face opposed to the opening in the hook 6. The main portion of the envelope-piece 10 seats against the bottom edges of the wings or side-ears 3 and is 65 soldered or otherwise secured thereto, as shown in Fig. 2.

The latch or keeper for closing the open mouth of the hook 6 consists in a substantially flat L-shaped lever 12, shown in detail in Fig. 6, held between the folded sides of the enclosing-member 10 and pivoted thereto by a pin or rivet 13 extending through a hole 14 in the lever and holes 15 in the piece 10. The lever or latch 12 is 70 provided with an extension 16 which projects beyond the side of the envelope-piece 10 and is bent to lie adjacent the side 3 of the clasp with a small ear 17 curled around to provide a finger-grip for rocking or turning the latch or lever 12 on its pivot-pin 13. When the lever 12 is turned into the position illustrated by full lines in Fig. 3 one of its legs 18 will project across the gap between the end of the beak 6 and the envelope-piece 10 to close the hook whereby to prevent the release of the clasp from the loop 7 on the watch or other part with which it is engaged.

Preferably, the latch or lever 12 is punched or indented to form a detent protuberance or teat 20 adapted to engage the edge of the envelope-strip 10 to hold the latch in closed position, as illustrated by full lines in Fig. 3. To open the clasp the latch or lever 12 is 95 swung around into the position illustrated by dotted lines in Fig. 3 by pressing the finger-grip 17. When the latch is swung into open position the detent protuberance 20 will slide in under the folded-over portion 100 of the latch-holding envelope 10, the sides of this member spring apart slightly for this purpose. The friction between the two parts 105

will then hold the latch in open position and when it is swung forward to close the beak of the hook 6 the detent 20 rides over the edge of the strip and snaps into place to hold it closed.

My improved clasp may be attached to the end of any usual type of watch-bracelet, such as a leather strap, a band of fabricated wire, or a link bracelet; in which latter case the 10 main element 2 of the clasp may have its box-like portion 9 shaped to conform to the links of the bracelet and adapted in some instances to enclose an inner sliding link. When fastened to the end of the strap, band or bracelet 15 the clasp is readily attached to the loop 7 on the watch 8 by hooking its beak 6 thereover, the latch or lever 12 being moved into open position for this purpose, as shown by the dotted lines in Fig. 3. After the hook 6 has 20 been engaged with the loop 7 on the watch 8 the latch or lever 12 is swung back to the position shown in full lines in Fig. 5 to project its leg 18 forwardly across the gap between the edge of the hook and the main 25 box-portion of the clasp. In this position the detent protuberance 20 snaps over the edge of the member 10 to secure the latch against accidental movement.

It will be observed that my invention provides a clasp of particularly neat and simple construction which may be manufactured from sheet-metal struck up in suitable dies. The present improved clasp does not require the use of a spring for closing its latch or 30 keeper and the arrangement of the latch is such as to provide against its derangement or getting out of order. The latch or keeper for the hook of the clasp being enclosed between the sides of the folded strip or envelope 10 is held firmly thereby and prevented from lateral play or lost motion on its pivot. Moreover, this construction braces 35 the latch throughout its main portion and the leg which projects forwardly and in under 40 the edge of the hook 6 is braced at this point so as to prevent any chance of the latch or keeper becoming bent or getting out of place. This construction, therefore, makes 45 for greater strength and durability of the whole clasp and renders the device particularly staunch and well adapted for men's 50 watch-bracelets or for other purposes where it is subjected to hard wear. By mounting 55 and enclosing the latch or keeper of the clasp in the manner described lateral strain on its pivot is eliminated and loosening of the joint of the latch avoided.

While I have herein described and illustrated a preferred embodiment of the invention it is to be understood that various modifications may be made in the structure and arrangement of the parts of the device which would fall within the spirit and scope of the appended claims. Therefore, without limiting 60 myself in this respect, I claim:

1. In an article of the type specified, the combination of a sheet-metal member having lateral wings projecting downwardly from its sides and a hook bent around in the same direction as the wings, a folded sheet-metal strip extending between the wings in parallel relation with the edge of the hook, and a latch-lever held between the folded sides of said strip and slidably therein to project its end across the opening of the hook. 70

2. In an article of the type specified, the combination of a member having a hooked beak and lateral wings extending downwardly from its sides in spaced relation to the edge of the beak, a folded strip secured to 80 the edges of said wings with its open side in opposed relation to the edge of the hook, and a latch slidable between the sides of the folded strip to project it across the opening of the hook. 85

3. In an article of the type specified, the combination of a member formed with a hook at its end, a folded strip held on said member with its open side in parallel relation with the edge of the hook, a latch-lever 90 held between the folded sides of the strip and pivoted thereto to adapt it to be projected across the opening of the hook, and a detent protuberance on said lever adapted to engage the edge of the folded strip to retain 95 the latch in closed relation with respect to the hook.

4. In an article of the type specified, the combination of a member provided with a hooked beak and having a parallel-sided portion formed with an open slot extending in opposite relation to the edge of the beak, and a keeper pivoted between the opposite walls of said parallel-sided portion to adapt it to be rocked on its pivot and projected through 105 the slot across the opening of the beak. 100

5. In a clasp for watch bracelets or similar articles, the combination of a sheet-metal member bent around at its end to form a hook with its free edge extending parallel to 110 the plane of the main portion of said member, and provided with a flat portion having parallel sides with a restricted opening therebetween extending in opposite parallel relation with the edge of the hook, and a latch 115 pivoted between the sides of the flat portion to adapt it to slide laterally across the edge of the hook to close the latter.

6. In an article of the type specified, the combination of a sheet-metal member having 120 a hook at its end bent around to bring its free edge parallel to the plane of the flat portion of said member, and provided with a folded portion having parallel sides spaced at a slight distance apart with their edges extending in parallel spaced relation with respect to the edge of the hook, and a latch pivoted to slide between the parallel sides of said folded portion to adapt it to swing 125 laterally across the edge of the hook. 130

7. In an article of the type specified, the combination of a sheet-metal member having lateral wings bent down from its sides and a hook curled around from its end, said member provided with a folded portion having opposite parallel sides extending between the wings on the member with its edges dis-
- posed parallel with the edge of the hook, and a latch held between the sides of the folded portion to adapt it to slide laterally across ¹⁰ the edge of the hook to close the latter.

In testimony whereof I affix my signature.

ALMYR L. NEWMAN.
